UNITED STATES PATENT OFFICE.

FRITZ FREDERICK UEHLING, OF PASSAIC, NEW JERSEY.

RECORDING GALVANOMETER.

Application filed January 27, 1927. Serial No. 164,091.

My invention relates to recording galvanometers or millivoltmeters, and embodies a novel method of transmitting the delicate motion of the galvanometer needle to a more rugged device for moving a pen or marker in proportion to changes in the reading of the galvanometer. Although my invention lends itself to any of the well known applications of the galvanometer, I am confining this description to one particular form, namely, that of a recording pyrometer in which the electro-motive force of a thermo-couple is recorded by the recording galvanometer, the latter being calibrated in degrees of temperature instead of in electrical units. My invention particularly relates to means for utilizing the delicate needle of a galvanometer, as a contact member for definitely closing electric circuits which control the recording device, the latter being operated by an independent source of power.

Figure 1 is a plan view of the recording galvanometer, and special relays by which it is controlled, and with which it is electrically connected.

Figure 2 is an enlarged plan view of the relays, a cross section through the galvanometer or millivoltmeter along the line A—A of Figure 1, and a diagrammatical arrangement of different parts of the mechanism and their electrical connections.

Figure 3 is an elevation of one of the relays, each of them being the same.

Figures 4, 5, 6 and 7 show different positions of mercury switches, hereinafter referred to as connectors.

The same numerals refer to the same parts in all of the illustrations.

A galvanometer or millivoltmeter is permanently fastened to a worm wheel 1, Figure 1, so that the axis of the pivoted coil or armature of the galvanometer, coincides with the axis of said wheel. The galvanometer consists of the usual permanent magnet 2, between the north and south poles of which, a coil or armature 3 is pivoted at 4 and 5, Figure 2. The electric current which tends to cause the coil 3 to rotate, passes through an insulated stud 6, a hair spring 7, pivoted coil 3, hair spring 8 and insulated stud 9. The reac-

tionary force which determines the position of the pivoted coil 3 and the needle 10 which is fastened to it, is caused by the hair springs 7 and 8. These elements thus constitute a well known form of galvanometer or millivoltmeter, the pivoted coil 3 and needle 10, tending to turn through a definite angle depending upon the magnitude of the electric current passing through the coil 3 in the manner stated.

In this particular application of my invention, the magnitude of the electric current which is measured by the needle 10 of the galvanometer, depends upon the temperature of a thermo-couple 11, the principle of which is well known and understood, said thermo-couple being placed in a medium, the temperature of which is to be recorded. The current thus created by the temperature of the thermo-couple passes through wire 12, binding post 13, and a flexible connection 14, Figures 1 and 2, thence through hair spring 7 and pivoted coil 3, Figure 2, thence through hair spring 8, flexible connection 15, a resistance 17, and wire 19 back to the couple 11, Figures 1 and 2. The resistance 17, which is held in position by binding posts 16 and 18, is a very important feature of my invention and will be referred to later.

The galvanometer, consisting of the different parts above mentioned, is fastened to the worm wheel 1, Figures 1 and 2, by means of a bracket 20, Figure 2. Wheel 1 is rotatably mounted on a stud 21, Figure 2, which stud is permanently fastened to the base 22. The worm wheel 1 meshes with a worm 23, Figures 1 and 2, and is in geared connection with a reversible motor 24 through shaft 25, worm wheel 26, worm 27, and shaft 28. The shaft 28 which extends from the motor and carries worm 27, is supported by a bearing 29, while the shaft 25 which carries worm 23 and worm wheel 26, the latter meshing with worm 27, is supported by bearings 30 and 31, Figure 1. It thus follows that as the motor 24 rotates in one direction, wheel 1 including the galvanometer and its needle 10, will also rotate in one direction, but at a very much reduced velocity, due to the reduction gear already described. Likewise when the motor 24 rotates

in the opposite direction, wheel 1 including the galvanometer and its needle 10 will also rotate in the opposite direction.

The motor 24 is operated by relays 35 and 36, Figure 1, one of which closes the circuit which operates the motor in one direction, and the other of which closes the circuit which operates the motor in the opposite direction. These relays are respectively actuated by a circuit which is closed when contact piece 32 at the end of needle 10 touches a contact disc 34, Figure 1, and a circuit which is closed when the contact piece 32 touches contact disc 33. When the contact piece 32 touches contact disc 33, it will cause the motor to rotate the wheel 1 with the galvanometer in a clockwise direction, and when the contact piece 32 touches contact disc 34, it will cause the motor 24 to rotate the wheel 1, including the galvanometer, in a counter-clockwise direction. Furthermore when the contact piece 32 touches neither the disc 33 or 34, then the motor will be dead and the wheel 1 to which the galvanometer is fastened will be stationary.

The circuits which actuate the relays, and those which operate the motor in one direction or the other, also the novel manner in which unfailing contact is made between the delicate needle 10 of the galvanometer, and the discs 33 or 34, will be presently described in complete detail.

The thermo-couple 11 is so connected with the galvanometer that an increase in its temperature will cause the needle 10 to rotate in the direction which will establish contact between contact piece 32 and disc 33. The circuit which is thus closed through the contact disc 33 will actuate the relay 36, which relay 35 will close the circuit through the motor 24 to turn the wheel 1 and the galvanometer in a clockwise direction. This motion of wheel 1 in a clockwise direction will continue until the contact piece 32 has freed itself from the contact disc 33, at which time the relay will cease to act and the motor will stop. Complete details of the relays 35 and 36 will be presently described. Should the temperature of the thermo-couple 11 increase still further, then the contact piece 32 will again touch the contact disc 33, thus again actuating the relay 36 which operates the motor to turn the wheel 1 and galvanometer still further in a clockwise direction until the contact piece 32 has again freed itself from the contact disc 33, when the relay will cease to act and the motor will stop.

Likewise should the temperature of the thermo-couple 11 drop, then the needle 10 including the contact piece 32 will turn in a clockwise direction, thus making contact between contact piece 32 and contact disc 34. The circuit which is thus closed through the contact disc 34, will actuate the relay 35, which relay will close the circuit through the

motor 24 to rotate the wheel 1 and galvanometer in a counter-clockwise direction. The motion of the wheel 1 in a counter-clockwise direction will continue until the contact piece 32 has freed itself from the contact disc 34, at which time the motor will stop. Should the temperature of the thermo-couple continue to drop, the contact piece 32 will again touch the contact disc 34, the wheel 1 and galvanometer will continue to rotate in a counter-clockwise direction, until the contact piece 32 has again freed itself from the disc 34. It is thus obvious that the wheel 1 will change its position in definite proportion to the temperature measured by the thermo-couple.

The circuits which include the motor 24, and which cause it to operate in one direction or the other, are illustrated in dot and dash lines, and are respectively closed by the special relays 35 and 36. The circuits which actuate the relays, are illustrated in dotted lines, the circuit which actuates relay 35 being closed when the contact piece 32 touches contact disc 34, and the circuit which actuates the relay 35 being closed when the contact piece 32 touches contact disc 33.

A very novel and important part of this invention, is the method which I use in assuring definite contact between the contact piece 32 of the delicate needle 10 of the galvanometer, and the respective contact disc 33 or 34. This consists of a clock or motor 41, Figure 1, or any other means for imparting motion to the contact discs 33 and 34, and an electrical resistance 17 which is included in both the circuit through the respective discs 33 and 34, and in the circuit passing through the galvanometer, which latter circuit in this particular form of my invention includes the thermo-couple 11. The manner in which the resistance 17 functions will be presently described. The clock 41 which rotates the contact discs 33 and 34, is supported by a bracket 42 which is fastened to the base 22 by screws 43 as illustrated. The clock drives the discs 33 and 34 through shaft 43 which is carried by bearings 44 and 45. The contact discs 33 and 34 are insulated from each other by insulation 46 and from the clock by insulation 47.

In each of the relays 35 and 36 are utilized three mercurial connectors 48, 49, and 50 and 48^a, 49^a and 50^a, respectively. These connectors are shown in detail, and in different positions by Figures 4, 5, 6 and 7. Each connector consists of a hermetically sealed glass bulb 51 containing mercury. Into one end of each bulb is sealed a wire 52 which extends into the bulb as illustrated, and protrudes to the outside of the bulb to permit making an electrical connection. Into the other end of each bulb is sealed another wire 53 which also extends into the bulb as illustrated, and protrudes to the outside to permit making

- electrical connections. Each connector is provided with a pocket, or well 54, into which extends the wire 53. Each bulb contains a globule of mercury 55, Figures 5 and 6.
- 5 When the bulb is so placed that the pocket 54 is on the right hand side, Figures 4 and 5, it is obvious that as the bulb is tilted in a clockwise direction, Figure 5, electric connections will be made through the mercury between the wires 52 and 53. On the other hand if the connector is tilted in a counter-clockwise direction, Figure 4, the mercury will break into two globules, some of it remaining in the pocket 54, thus breaking electric connections between wires 52 and 53. Likewise if the connector is so placed that the pocket 54 is on the left hand side, Figures 6 and 7, it is obvious that as the connector is tilted in a counter-clockwise direction, Figure 7, electric connection will be made through the mercury between wires 52 and 53, and as the connector is tilted in a clockwise direction, Figure 6, electric connection will be broken between wires 52 and 53.
- 25 Connectors 48, 49, and 50, and connectors 48^a, 49^a and 50^a of the relays 35 and 36 respectively, are mounted on tiltable blocks 56 and 56^a, which are respectively pivoted on bearings 57 and 58, and bearings 59 and 60. These bearings are fastened to base 61, and to base 62, of the respective relays. A pair of stationary electro-magnets 63 are fastened to the base 61 of relay 35 by means of a bracket 64, and a pair of stationary electro-magnets 35 65 are fastened to the base 62 of relay 36 by means of a bracket 66. The purpose of magnets 63 are to attract a soft iron armature 67 which is screwed fast to the tiltable block 56 as illustrated. The armature 67 and the 40 tiltable block to which it is fastened are held in their normal position by a spring 68, the tension of which is adjustable by means of screw 69. The armature 67 and the tiltable block 56 to which it is fastened, are limited 45 in motion by the adjusting screw 70, which determines how far away from the magnets 63, the armature 67 may be pulled by the spring 68. Furthermore the distance which the magnets 63 may move armature 67 against 50 the tension of the spring 68, is limited by the adjusting screw 71. The adjusting screws 69 and 70 are threaded through a stationary bracket 72 which is screwed fast to the base 61. The adjusting screw 71 is threaded 55 through bracket 64 which supports the magnets 63, and which bracket, as already stated, is also screwed fast to the base 61. It is obvious from the above that, when the magnets 63 are energized, they will attract the armature 67, thus causing the block 56, including the connectors 48, 49 and 50, to tilt in one direction, and when the magnets 63 are de-energized, the spring 68 will cause them to tilt in the opposite direction.
- 65 The construction of relay 36 is exactly the same as that of relay 35, so that when magnets 65 are energized they will cause the block 56^a, including the connectors 48^a, 49^a and 50^a, to tilt in one direction, and when the magnet 65 are deenergized, the spring 73 will cause them to tilt in the opposite direction.
- The connectors 48 and 49 of relay 35 are included in the circuit which operates the motor 24 to turn wheel 1 and galvanometer 2 in a counter-clockwise direction. They are fastened to the tiltable block 56 by means of a clip 74, and are so placed on the tiltable block 56 that, when they are tilted by magnets 63, they will assume the position illustrated in Figure 7, thus making electrical connections in each of them; and when they are brought back to their normal position by the spring 68 they will assume the position illustrated in Figure 6, thus breaking electrical connection in each of them. The connector 50 is fastened to the tiltable block 56 by means of clip 75, and is included in the same circuit which includes magnets 63, and which is closed when contact is made between contact piece 32 of galvanometer needle 10 and contact disc 34. 90 The connector 50 is so placed on the tiltable block 56 that, when it is tilted by the magnets 63, it will assume the position illustrated in Figure 4 thus breaking electrical connections; and when it is brought back to its normal position by the spring 68, it will assume the position illustrated in Figure 5, thus making electrical connections. It thus follows that when contact is made between contact piece 32 and contact disc 34, magnets 63 will become energized and tilt the block 56 with its connectors 48, 49 and 50. The tilting of connector 50 by the action of magnets 63, will break the circuit through the magnets 63, and permit the spring 68 to pull the tiltable block 100 56, with its connectors, back to the normal position in which, as already stated, electrical connections through connector 50 is again established. If electrical contact still exists between contact piece 32 and disc 34, this cycle 110 will repeat itself. In other words, so long as the circuit through contact piece 32 and disc 34 is closed, so long will the tiltable block 56, with its connectors 48, 49 and 50, continue to oscillate. This oscillation causes an intermittent closing and opening of the circuit through connectors 48 and 49, which will operate the motor 24 to turn the wheel 1 in a counter-clockwise direction, until contact between contact piece 32 and disc 34 is broken. 115 When this happens the magnets 63, which are included in the circuit through disc 34, will cease to function, and the connectors of relay 35 will assume their normal position by the action of the spring 68. In this position, as already stated, the circuit through connectors 48 and 49 will be broken, thus causing the motor which has been turning the galvanometer in a counter-clockwise direction to stop.

Likewise connectors 48^a and 49^a of relay 36 are included in the circuit which operates the motor 24 to turn wheel 1 and galvanometer 2 in a clockwise direction. They are fastened to the tiltable block 56^a by means of a clip 76, and are so placed that when they are tilted by magnets 65 they will assume the position illustrated in Figure 7, thus making electrical connection through each of them; 10 and when they are brought back to their normal position by the spring 73, they will assume the position illustrated in Figure 6, thus breaking electrical connection through each of them. The connector 50^a is fastened to the 15 tiltable block 56^a by means of clip 77, and is included in the same circuit which includes magnets 65, and which is closed when contact is made between contact piece 32 of the galvanometer needle 10, and contact disc 33. 20 The connector 50^a is so placed on the tiltable block 56^a that, when it is tilted by the magnets 65, it will assume the position illustrated in Figure 4, thus breaking electrical connection; and when it is brought back to its normal 25 position by the spring 73, it will assume the position illustrated in Figure 5, thus making electrical connection. It thus follows that, when contact is made between contact piece 32 and disc 33, magnets 65 will become energized 30 and tilt the block 56^a with its connectors 48^a, 49^a and 50^a. The tilting of connector 50^a by the action of magnets 65 will break the circuit through said magnets and permit the spring 73 to pull the tiltable block 56^a, with 35 its connectors, back to the normal position in which electrical connection through connector 50^a is again established. If electrical contact still exists between contact piece 32 and disc 33, this cycle will repeat itself. In other 40 words, so long as electrical contact exists between contact piece 32 and disc 33, so long will the tiltable block 56^a with its connectors 48^a, 49^a and 50^a continue to oscillate. This 45 oscillation causes an intermittent closing and opening of the circuit through connectors 48^a and 49^a, which will operate the motor 24 to turn the wheel 1 in a clockwise direction until contact between contact piece 32 and disc 33 is broken. When this happens, the magnets 50 65 which are included in the circuit through disc 33 will cease to function and the connectors of relay 36 will assume their normal position by the action of the spring 73. In this position, as already stated, the circuit through connectors 48^a and 49^a will be broken, thus causing the motor which has been turning the galvanometer in a clockwise direction to stop. 55

It will be noted from the above that the purpose of the connectors 48 and 49, and 48^a and 49^a respectively, Figure 2, is to close the proper circuits for operating the motor 24, Figure 1, to turn the wheel 1, on which the galvanometer is mounted, in a counter-clockwise, or clockwise, direction depending upon 60 which of the magnets 63 or 65 are energized.

The motor 24, as previously stated, is series wound, so that its direction of operation may be reversed by reversing the direction of the current through its armature without changing the direction of the current through its field. The field 78, and the armature 79 with its brushes 80 and 81, all of motor 24, are diagrammatically illustrated in Figure 2. When the circuit through connectors 48 and 49 has been closed by the action of magnets 63, in the manner already stated, then the circuit which operates the motor to turn the galvanometer in counter-clockwise direction, starts at battery 82 Figure 2, passes through wires 83 and 84 to binding post 85, thence through flexible connection 86, connector 49, and flexible connection 87 to binding post 88, thence through wire 89, through brush 81, armature 79, and brush 80 of the motor, thence through wires 90 and 91 to binding post 92, from binding post 92 through flexible connection 93, connector 48, and flexible connection 94 to binding post 95, thence through wires 96, 97, and the field 78 of the motor, back to the battery. 90

Likewise when the circuit through connectors 48^a and 49^a has been closed by the action of magnets 65, in the manner already stated, then the circuit which operates the motor to turn the galvanometer in a clockwise direction starts at battery 82, passes through wires 83 and 98 to binding post 99, thence through flexible connection 100, connector 48^a, and flexible connection 101 to binding post 102, from binding post 102 through wires 103 and 90, thence through brush 80, armatures 79 and brush 81 of the motor, from brush 81 through wires 89 and 104 to binding post 105, from binding post 105 through flexible connection 106, connector 49^a, and flexible connection 107 to binding post 108, and thence through wires 109, 97, and the field 78 back to the battery. In order to facilitate the tracing of the circuits just described, the one which includes connectors 48 and 49 and which is closed when magnets 63 are energized, follows the straight line arrows, while the circuit which includes connectors 48^a and 49^a, and is closed when magnets 65 are energized, follows the wavy line arrows. 110

The circuits which energize magnets 63 and 65 respectively are independent of the circuits which operate the motor. The circuit which includes magnets 63, starts at battery 37, passes through wire 40 to magnets 63, from magnets 63 through wire 110 to binding post 111, from binding post 111 through flexible connection 112, connector 50, and flexible connection 113 to binding post 114, from binding post 114 through wire 39 to bearing 44, and contact disc 34, Figure 1, and thence, when contact piece 32 touches contact disc 34, to needle 10, from needle 10 through hair spring 8, stud 9 and flexible 120 125 130

connection 15 to binding post 16, Figure 2, from binding post 16 through resistance 17 to binding post 18, and thence back to the battery through wire 38.

5 Likewise the circuit which includes magnets 65 starts at battery 115, passes through wire 116 to magnets 65, from magnets 65 through wire 117 to binding post 118, from binding post 118 through flexible connection 119, connector 50^a and flexible connection 120 to binding post 121, from binding post 121 through wire 122, bearing 45, and contact disc 33, Figure 1, and thence, when contact piece 32 touches contact disc 33, to needle 10, 70 from needle 10 through hair spring 8, stud 9, and flexible connection 15 to binding post 16, Figure 2, from binding post 16 through resistance 17 to binding post 18 and thence back to the battery 115 through wire 38.

10 It will be noted that wire 38 is connected with the positive terminal of battery 37, and with the negative terminal of battery 115. The purpose of this is to cause a current to flow in one direction through the resistance 17, when the circuit which includes magnets 63 and battery 37 is closed by contact between 75 32 and 34, and to cause a current to flow in the opposite direction through the resistance 17, when the circuit which includes magnets 65 and battery 115 is closed by contact between 80 32 and 33 Figure 2. It is obvious that any current passing through the resistance 17 will cause a drop in potential across the resistance, which drop, or difference in potential 85 between binding posts 16 and 18, will in turn cause a current to flow through the galvanometer in one direction or the other, depending upon the direction of the flow of current through the resistance. In other 90 words, when there is a flow through needle 10, hair spring 8, flexible connection 15, resistance 17, and wire 38, Figures 1 and 2, there will be a difference in potential between the binding posts 16 and 18 due to the drop across 95 the resistance 17, which will cause a flow from resistance 17, through wire 19, thermo-couple 11, wire 12, flexible connection 14, pivoted coil 3, and flexible connection 15, back to the resistance 17.

100 10 It thus follows that the slightest pressure of contact piece 32 against the slowly rotating disc 33, as caused by the electro-motive force of the thermo-couple 11, will cause some current to flow through the circuit which includes needle 10, flexible connection 15, resistance 17, battery 115 and magnets 65 of relay 36. The polarity of battery 115 is such that the drop across the resistance 17 will cause 105 a flow through the thermo-couple and galvanometer, in the proper direction, to increase the turning moment of the pivoted coil 3, beyond that established by the temperature of the thermo-couple, Figure 2, thus increasing the pressure of the rubbing contact between 110 contact piece 32 and the rotating disc 34. As the contact pressure between 32 and 34 increases, in the manner above stated, the flow through resistance 17, and magnets 65 will also increase, thus still further increasing the drop through resistance 17. This increased drop across resistance 17 will obviously also increase the flow through the thermo-couple and galvanometer so that contact piece 32 will be forced still 115 tighter against disc 33. The pressure between the contact piece 32 and the rotating disc 33, thus builds up until sufficient contact force has been established to actuate the relay 35. As previously stated, with each oscillation of the relay 36, the circuit through magnets 65 and disc 33 will be broken in the connector 50^a, thus permitting the needle 10 to adjust itself to the position determined by the effect of the thermo-couple alone. If, in this position, the contact piece 32 still touches disc 33, the above described action will repeat itself until the motor 24 has turned the galvanometer and needle 10 sufficiently in a counter-clockwise direction to entirely free the contact piece 32 from disc 33.

120 15 Likewise, the slightest pressure of contact piece 32 against the slowly rotating disc 34, as caused by a drop in the electro-motive force of the thermo-couple 11, will cause some current to flow through the circuit which includes needle 10, flexible connection 15, resistance 17, battery 37 and magnets 63 of relay 35. The polarity of battery 37 is such that the drop across the resistance 17 will cause a flow through the thermo-couple and galvanometer in the proper direction to increase the turning moment of the pivoted coil 3, beyond that established by the temperature of the thermo-couple, Figure 2, thus increasing the pressure of the rubbing contact between 125 contact piece 32 and the rotating disc 34. As the contact pressure between 32 and 34 increases, in the manner above stated, the flow through resistance 17, and magnets 63 will also increase, thus still further increasing the drop through resistance 17. This increased drop across resistance 17 will obviously also increase the flow through the thermo-couple and galvanometer, so that contact piece 32 will be forced still tighter against disc 34. The pressure between the contact piece 32 and the rotating disc 34, thus builds up until sufficient contact force has been established to pass enough current to actuate the relay 35. As previously stated, with each oscillation of the relay 36, the circuit through magnets 63 and disc 34 is broken in the connector 50^a, thus with each oscillation of the relay the needle 10 is permitted to adjust itself to the position determined by the effect of the thermo-couple alone. If, in this position, the contact piece 32 still touches disc 34, the above described action will repeat itself until the motor 24 has turned the galvanometer and needle 10 sufficiently in a clockwise direction.

rection to entirely free the contact piece 32 from the disc 34.

It thus follows that the slightest electrical contact between contact piece 32 and either of 5 the contact discs 34 or 33, as may be caused by changes in the temperature of the couple 11, will be sufficiently augmented by the action of resistance 17, to insure the operation of either relay 35 or 36 with which said contacts 10 discs are respectively connected.

An arm 125 which carries a marker 126 is permanently fastened to the wheel 1, Figure 1. The marker 126 rests against a chart 127 which chart is driven by a clock not shown. 15 It therefore follows that since the wheel 1 changes its position in proportion to changes in the temperature of the couple 11, all in the manner described, the chart 127 may be calibrated in suitable units to provide a continuous and permanent record of the temperature changes.

Although I have illustrated the resistance 17 in a definite position, it is obvious that it may be located in different parts of the circuits referred to. For example, resistance 25 17 may be located anywhere between the junction of the wires 38 and 19, and the point at which they connect with the pivoted coil 3, Figure 2. Furthermore, the hair spring 8, 30 if properly designed, may in itself have the proper resistance to produce the required results.

Having thus described my invention what I claim as new and desire to secure by Letters Patent is:

1. In a recording galvanometer, the combination with a permanent magnet, of a coil pivoted between the north and south pole pieces of the magnet, a hair spring for resisting the motion of the pivoted coil, an indicating needle fastened to the coil, a contact piece with which the needle makes electrical contact when reflected to a given position, a circuit which includes the pivoted coil and 40 the hair spring, and a circuit which includes the hair spring, the needle, and the contact piece.

2. In a device of the class described, the combination with an electrical resistance, of 50 a galvanometer with an indicating needle, said galvanometer being shunted across the resistance, an electric contact piece in the path of the needle, and a circuit which includes the resistance, the needle and the contact piece.

3. In a recording galvanometer, the combination with a galvanometer, of an electrical resistance, an electric circuit which includes both the galvanometer and the electrical resistance, a battery of a given polarity, a second circuit which includes the battery and the resistance, a second battery of opposite polarity to that of the first, and a third circuit which includes the second battery and 60 the resistance.

4. In a device of the class described, the combination with a galvanometer having an indicating needle, of an electrical resistance, a contact piece with which the needle collides when deflected to a given position, an electric circuit which includes the needle and contact piece in series, and the resistance and the galvanometer in parallel, and a second electric circuit which includes the resistance and the galvanometer in series.

5. In a device of the class described, the combination with a reversible motor, of a circuit which operates the motor in one direction, a second circuit which operates the motor in the opposite direction, a relay which 70 closes the first circuit, a second relay which closes the second circuit, a galvanometer, an electrical resistance, a third circuit which includes the galvanometer and the electrical resistance, a fourth circuit which includes the electrical resistance and the first relay, and a fifth circuit which includes the electrical resistance and the second relay.

6. In a device of the class described, the combination with a galvanometer having an 90 indicating needle, of a contact disc for making electrical contact between itself and the needle, a second contact disc for making electrical contact between itself and the needle, a resistance, an electric circuit which includes the first contact disc, the needle and the resistance, a second electric circuit which includes the second contact disc, the needle and the resistance, and a third circuit which includes the galvanometer and the resistance.

7. In a device of the class described, the combination with a galvanometer having an indicating needle, of a switch, a motor, a circuit for operating the motor in one direction which includes the switch, a second switch, a second circuit for operating the motor in the opposite direction which includes the second switch, an electrical means for closing the first switch, a second electrical means for closing the second switch, a contact disc with which the needle of the galvanometer collides when deflected in one direction, a third circuit which includes the first electrical means, the needle and the contact disc, a second contact disc with which the needle of the galvanometer collides when deflected in the opposite direction, a fourth circuit which includes the second electrical means, the needle and the second contact piece, an electrical resistance which is included in both the third and fourth circuits, and a fifth circuit which includes the resistance and the galvanometer.

8. In a device of the class described, the combination with a rotatably mounted galvanometer having an indicating needle, of a switch, a motor, a circuit for operating the motor in one direction which includes the switch, a second switch, a second circuit for operating the motor in the opposite direction

which includes the second switch, electrical means for closing the first switch, a second electrical means for closing the second switch, a contact piece with which the needle of the 5 galvanometer collides when deflected in one direction, a third circuit which includes the first electrical means, the needle and the contact piece, a second contact piece with which the needle collides when deflected in the opposite direction, a fourth circuit which includes the second electrical means, the needle and the second contact piece, an electrical resistance which is included in both the third and fourth circuits, a fifth circuit which includes the resistance and the galvanometer, and a geared connection between the motor 10 and the galvanometer for rotating the latter.

9. In a device of the class described, the combination with a rotatably mounted galvanometer, of electrical means for rotating the galvanometer in one direction, electrical means for rotating the galvanometer in the opposite direction, an electrical resistance, an electric circuit which includes the resistance 20 and the first rotating means, an electric circuit which includes the resistance and the second rotating means, and a third electric circuit which includes the galvanometer and the resistance.

10. In a device of the class described, the combination with a rotatably mounted galvanometer having an indicating needle, of electrical means for rotating the galvanometer in one direction, electrical means 30 for rotating the galvanometer in the opposite direction, a contact piece for making electrical contact with the needle when the needle is deflected in one direction, a second contact piece for making electrical contact with the needle when the needle is deflected in the opposite direction, an electrical resistance, an electric circuit which includes the first rotating means, the resistance, the needle, and the first contact piece, a second electric circuit which includes the second rotating means, the resistance, the needle, and the second contact piece, automatic means for consecutively opening and closing the first circuit when the needle is in contact with the 40 first contact piece, automatic means for consecutively opening and closing the second circuit when the needle is in contact with the second contact piece, and a third electric circuit which includes the resistance and the galvanometer.

11. In a device of the class described, the combination with a rotatably mounted galvanometer having an indicating needle, of electrical means for rotating the galvanometer in one direction, electrical means for rotating the galvanometer in the opposite direction, a relay for actuating the first rotating means, said relay comprising a connector, an electro-magnet for tilting the connector in one direction and a spring for tilt-

ing the connector in the opposite direction, a second relay for actuating the second rotating means, said second relay comprising a second connector, a second electro-magnet for tilting the second connector in one direction 70 and a spring for tilting the second connector in the opposite direction, a contact piece for making electrical contact with the needle when the needle is deflected in one direction, a second contact piece for making electrical contact with the needle when the needle is deflected in the opposite direction, an electrical resistance, an electric circuit which includes the resistance, the needle, the first contact piece, the first connector and the first 75 magnet, a second electric circuit which includes the resistance, the needle, the second contact piece, the second connector and the second magnet, and a third circuit which includes the resistance and the galvanometer.

12. In a device of the class described, the combination with a galvanometer having an indicating needle, a contact piece with which the needle makes electrical contact when deflected to a given position, an electrical resistance, an electric circuit which includes 90 the galvanometer and the resistance, and a second electric circuit which includes the needle, the contact piece, and the resistance.

13. In a device of the class described, the combination with a galvanometer having an indicating needle, of an electrical resistance, a contact piece with which the needle collides when deflected in one direction, a second contact piece with which the needle collides when 95 deflected in the opposite direction, a circuit which includes the galvanometer and the resistance, a battery, a second circuit which includes the battery, the resistance, the needle and the first contact piece, a second battery, 100 and a third circuit which includes the second battery, the resistance, the needle and the second contact piece.

14. In a device of the class described, the combination with a galvanometer having an indicating needle, of a switch, an electro-magnet for opening the switch, an electric circuit for energizing the magnet which circuit includes the switch, automatic means for closing the switch when the magnet is de- 110 energized, a second switch, a second electro-magnet for opening the second switch, a second circuit for energizing the second magnet which circuit includes the second switch, automatic means for closing the second switch 115 when the second magnet is deenergized, an electrical resistance which is included in both of the circuits, a contact piece for making electrical contact between itself and the needle to close the first circuit, a second contact piece for making electrical contact between itself and the needle to close the second circuit, and a third circuit which includes the resistance, and the galvanometer.

15. A method for preventing adhesion be- 130

- between a delicately pivoted needle such as the needle of a galvanometer and an electrical contact piece when such a needle is used to close a circuit between itself and the contact piece, said method consisting in moving the contact piece by means of a clock or any other motive means in a plane approximately at right angles to the plane in which the needle moves, thus providing a rubbing effect between the needle and contact piece when they touch each other.

16. In a device of the class described, the combination with a tiltably mounted frame, of an electromagnet for tilting the frame in one direction, automatic means for tilting the frame in the opposite direction when the magnet is deenergized, a mercurial switch fastened to the tilttable frame, said switch being open when the frame has been tilted by the magnet and closed when tilted by the automatic means, a second mercurial switch fastened to the tilttable frame, a third mercurial switch fastened to the tilttable frame, said second and third switches being closed when the frame has been tilted by the magnet and open when tilted by the automatic means, a second tiltably mounted frame, a second electro-magnet for tilting the frame in one direction, automatic means for tilting the second frame in the opposite direction when the magnet is deenergized, a fourth mercury switch fastened to the second tilttable frame, said fourth switch being open when the second frame has been tilted by the magnet and closed when tilted by the automatic means, a fifth mercury switch fastened to the second frame, a sixth mercury switch fastened to the second frame, said fifth and sixth switches being closed when the frame has been tilted by the magnet and open when tilted by the automatic means, a second contact piece with which the needle makes contact when it turns in one direction, a second contact piece with which the needle makes contact when it turns in the opposite direction, an electric circuit which includes the needle, the first contact piece, the first switch and the first magnet, a second electric circuit which includes the needle, the second contact piece, the fourth switch and the second magnet, a motor, a third electric circuit for operating the motor in one direction said third circuit including the second and third mercury switches, a fourth circuit for operating the motor in opposite direction said fourth circuit including the fifth and sixth mercury switches, a rotatably mounted support for carrying the pivoted needle, and a geared connection between the motor and the support.

FRITZ FREDERICK UEHLING.

17. In a device of the class described, the combination with a tiltably mounted frame, of an electromagnet for tilting the frame in one direction, automatic means for tilting the frame in the opposite direction when the magnet is deenergized, a mercurial switch fastened to the tilttable frame, said switch being open when the frame has been tilted by the magnet and closed when tilted by the automatic means, a second mercurial switch fastened to the tilttable frame, a third mercurial switch fastened to the tilttable frame, said second and third switches being closed when the frame has been tilted by the magnet and open when tilted by the automatic means, a second tiltably mounted frame, a second electro-magnet for tilting the frame in one direction, automatic means for tilting the second frame in the opposite direction when the magnet is deenergized, a fourth mercury switch fastened to the second tilttable frame, said fourth switch being open when the second frame has been tilted by the magnet and closed when tilted by the automatic means, a fifth mercury switch fastened to the second frame, a sixth mercury switch fastened to the second frame, said fifth and sixth switches being closed when the frame has been tilted by the magnet and open when tilted by the automatic means, a second contact piece with which the needle makes contact when it turns in one direction, a second contact piece with which the needle makes contact when it turns in the opposite direction, an electric circuit which includes the needle, the first contact piece, the first switch and the first magnet, a second electric circuit which includes the needle, the second contact piece, the fourth switch and the second magnet, a motor, a third electric circuit for operating the motor in one direction said third circuit including the second and third mercury switches, a fourth circuit for operating the motor in opposite direction said fourth circuit including the fifth and sixth mercury switches, a rotatably mounted support for carrying the pivoted needle, and a geared connection between the motor and the support.

FRITZ FREDERICK UEHLING.
